ABSTRACT OF THE DISCLOSURE

A terminal device comprising a strip of heat shrinkable plastic material having a plurality of passageways therethrough in each of which is located a socket contact for receiving a pair of conductor terminating pins. Once all of the pins have been properly located, the strip is shrunk down around them to firmly secure them in place and to establish good electrical contact between the pins and the socket contact.

BACKGROUND OF THE INVENTION

Various mechanical terminal devices have been provided for establishing proper electrical connections between groups of electrical wires. Most of these devices rely on some type of spring biased socket contact to grasp the end of a suitable terminating pin which is crimped or otherwise fastened to the end of the conductor. The pressure of the spring portion of the socket contact on the pin establishes a wiping action between the two surfaces and provides the electrical contact. The socket contacts are either single ended with suitable connections formed on the device between pairs of them or are double ended and provide their own electrical contact. While such terminal devices are satisfactory for many applications, they are not as reliable as desired because the force exerted on the pin by the spring tines of the socket contact is often not great enough to withstand the forces, such as vibration, tending to pull the conductor out of the contact. Moreover, the devices of this type offer no environmental protection to the contact and thus special provision must be made for such protection.

SUMMARY OF THE INVENTION

According to the present invention, a terminal device is provided in which a plurality of double ended socket contacts are embedded in passageways formed in a strip of heat recoverable material. The spring forces of the contact are sufficient to hold the pins which are attached to the various conductors in place until the wiring assembly is completed and checked. The strip of material can then be heat recovered so as to cause the spring tines of the socket contacts to engage the pins even more firmly to produce a superior electrical contact, and also to engage the portion of the pins exterior of the socket contact to securely grasp them and prevent their retraction from the terminal strip. The plastic material of which the strip is made provides good environmental protection as it completely encapsulates the electrical connection. The device of the present invention has the further advantage of having the ability to be heated and shaped into unique configurations and cooled to allow mounting in irregular areas. While the conductors are prevented from being withdrawn under normal operating conditions, if it be-

2

comes desirable to withdraw them, the terminal strip can again be heated so that the material presses against the pins with only elastic force, thus permitting removal of the pins with only slightly greater difficulty than was involved before shrinkage.

It is therefore an object of the present invention to provide a terminal device for electrical conductors utilizing a strip of heat shrinkable material.

These and other advantages of the present invention will become more apparent upon reference to the accompanying description and drawings in which:

BRIEF DESCRIPTION OF THE DRAWINGS

FIG. 1 is a perspective view of a strip of heat recoverable material as used in the present invention together with a typical socket contact;

FIG. 2 is a cross-sectional view taken along lines 2—2 of FIG. 1;

FIG. 3 is a cross-sectional view similar to FIG. 2 but after the material has been partly recovered around mandrels;

FIG. 4 is a cross-sectional view similar to FIG. 2 but showing the terminal device ready to receive a pair of pins;

FIG. 5 is a cross-sectional view of the terminal device of the present invention after the pins have been installed and the material heat recovered;

FIG. 6 is a cross-sectional view of a modification of the terminal device showing pins partially inserted therein;

FIG. 7 is a cross-sectional view of the device of FIG. 6 after the pins have been installed and the material heat recovered.

DESCRIPTION OF THE INVENTION

Turning now to the drawings, a block or strip 10 of heat recoverable material is molded or otherwise provided with a plurality of passageways 11 which extend completely through the strip. Any polymeric material capable of being crosslinked such as by irradiation or chemical treatment may be utilized in the present invention. Preferably, the polymeric material is a heat recoverable material capable of having the property of elastic memory imparted to it. Typical heat recoverable materials include crosslinked polymers, for example, crosslinked polyolefins; crosslinked polyvinylchloride; crosslinked polyvinylidene halides; for example, crosslinked polyvinylidene fluoride; crosslinked ethylenevinylacetate copolymers; crosslinked ethyleneethylacrylate copolymers; crosslinked polyamides; etc. The strip 10 could also be fabricated of noncrystalline polymeric materials capable of having the property of plastic or elastic memory imparted thereto such as polyurethane and ionmers and elastomers such as silicone. Materials having the property of plastic memory or elastic memory are equally useful in the present invention; therefore these terms are used interchangeably herein and are meant to be mutually inclusive.

The strip 10 is molded with the holes 11 and then each hole is expanded by heating the material above its crystalline melting point and inserting a steel rod having a diameter larger than the diameter of the original hole. Once the parts cool the rods are removed. The material around the holes is thus dimensionally changed from an original heat stable form to an independently heat un-

stable form capable of moving in the direction of its original form upon the application of heat alone.

Positioned within each of the holes 11 in the strip 10 is a double ended socket contact 12 which may be of the conventional type, i.e., a tube of copper or the like slotted at each end to form spring tines which are collapsed on each other to form an elliptical entry. They may also take the form of a tubular member which is slotted at each end but in which the tines are not collapsed on each other prior to heat recovery of the strip 10, or in which the tines are expanded to form a tapered entrance. In order that the strip 10 will retain the socket contacts 12 and form a stop shoulder for the pin contacts, a pair of mandrels 13 and 14 are inserted into the ends of each of the holes 11 as shown in FIG. 3. The ends of the mandrels 13 and 14 have a diameter sufficiently large to separate the tines of the contact 12 so that recovery of the strip 10 will not cause them to be forced together to such a degree as to prevent the access of the pin contacts. The strip 10 is then heated to above its heat recovery temperature so that it shrinks down around the mandrels and around the contact 12. Once the part has cooled, the mandrels 13 and 14 are removed leaving the double ended socket 12 captured in the center of the passageway 11. Because a small amount of recovery occurs after the mandrels are removed, the holes recover an additional small amount. The initial spreading of the tines by the mandrels must be enough to allow for this additional shrinkage. The resulting structure is shown in FIG. 4. As can be seen, the center portion of the contact 12 is firmly engaged by the material of the strip 10 while the tines are spaced from the wall so that they can receive the pin contacts.

The terminal device is now ready to receive pins 16 and 17 which terminate the ends of conductors 18 and 19, respectively. As shown, these pins are provided with a tapered forward end 20 for ease of insertion and a circular section 21 behind the taper. They are also provided with a collar 22 which serves as a locating shoulder. The pins 16 and 17 are inserted into the passageway 11 until the collar 22 abuts the ends of the tines 15. The pins are held in position by the tines 15 which provide a wiping action on the section 21 of the pin.

After all of the conductors have been positioned and the circuit tested or checked to determine that it has been correctly wired, the strip 10 is again heated to above its heat recovery temperature. This causes the material surrounding the holes 11 in the strip 10 to recover completely down around the contacts and force the spring tines tight around the pins. The recovery force of the shrinking of the crosslinked material helps to provide a good electrical contact. The pins cannot be removed because the material of the strip 10 recovers down around the collar of the pin and moves into slots 23 formed in the pin for that purpose. The final structure is shown in FIG. 5. As will be obvious to those skilled in the art, proper selection of the material from which the strip 10 is fabricated will result in a moisture seal being formed around the pins or, if desired, only a moisture barrier or no seal at all.

Once the material of the strip 10 has been heat recovered down around the pins 16 and 17, it is very difficult for them to be withdrawn and thus the terminal device is extremely resistant to degradation of the electrical contacts by vibration or other external forces. Moreover, the terminal device inherently provides its own environmental protection. If it is desired to again remove the pins, this can be accomplished by heating the strip to above the heat recovery temperature of the material from which it is fabricated. If this is done, only the elastic force of the material will press against the pins and they can be removed with only slightly greater difficulty than was involved before shrinkage of the strip 10. It will be obvious to those skilled in the art that the strip 10 can be molded in any desired shape so that the ter-

inal device is extremely versatile. It will also be obvious to those skilled in the art that the shape of the pins and the nature of the socket contact can be varied to suit any particular purpose without departing from the scope of the present invention.

Such a modified pin and socket contact construction is shown in FIGS. 6 and 7. In these figures, the socket contact 25 has tines 26 which extend outwardly to form a tapered pin receiving opening. The tines 26 are provided with a ridge 27 which cooperates with a groove 28 formed in the pin 29. The pin 29 is provided with a collar 30 which engages the ends of the tines to locate the pin. The configuration of the assembly after recovery is shown in FIG. 7.

As a specific example of the manner in which such a terminal strip can be constructed, a slab of 0.188 inch thick chemically crosslinked polyolefin was cut into a strip one inch wide. Holes 0.375 inch apart were then drilled across the width of the strip with a 0.062 inch drill. The material was then heated above the crystalline melting point and the holes expanded by inserting a 0.150 inch steel rod into each hole. Once the parts had cooled, the rods were removed and a two-piece, stepped mandrel having an outside diameter of 0.100 inch was inserted into each hole, the mandrels carrying the socket contacts. The part was again heated causing it to recover down on the mandrels. Once the part cooled, the mandrels were removed leaving the double ended sockets positioned within the strip. The socket members each were made of 0.010 inch beryllium copper former into a tube .500 inch long having a 0.100 inch inside diameter. The tube was slotted 0.188 inch deep by 0.015 inch wide from each end on the opposite side from the formed edge. A section was also taken out of the center of the tube to insure maximum spring of each tine. The pins were then inserted and the material again heated to above its recovery temperature to cause it to recover around the pins and socket contact in the manner previously described.

What is claimed is:

1. A device for receiving and holding a plurality of objects comprising: a block of heat recoverable material having a plurality of holes formed therein, the material around at least two of said holes having been dimensionally changed from an original heat stable form to an independently heat unstable form capable of moving in the direction of its original form upon the application of heat alone; and clamping means positioned within each of said dimensionally changed holes and adapted to mechanically engage in each of said dimensionally changed holes at least one of said objects, said material of said block being partially recovered to hold said clamping means in place, the device being further heat recoverable to encapsulate said clamping means and terminal portions of said objects, and admitting of the subsequent removal of the encapsulated terminal portions upon the application of heat.

2. The device of claim 1 wherein said holes extends through said block and wherein each of said clamping means has two ends, each of said ends being adapted to mechanically engage one of said objects.

3. The device of claim 1 wherein said clamping means comprise a tubular metallic members having flexible portions bent inwardly by said partial recovery of said material.

4. The device of claim 2 wherein said clamping means comprise a double ended socket contacts.

5. A device for receiving and holding a plurality of pins terminating corresponding electrical conductors, comprising: a block of heat recoverable material having a plurality of holes formed therethrough, the material around at least two of said holes having been dimensionally changed from an original heat stable form to an independently heat unstable form capable of moving in the direction of its original form upon the application of heat alone; and a plurality of double ended socket contacts

each adapted to mechanically engage a pair of said pins, each of said contacts being positioned within one of said dimensionally changed holes, said material of said block being partially recovered around said contacts to hold them in place, the device being further heat recoverable to encapsulate said contacts and said pins and admitting of the subsequent removal of the encapsulated pins upon the application of heat.

6. A terminal assembly comprising: a block of heat recoverable material having a plurality of holes formed therethrough; a plurality of double ended socket contacts, one of said socket contacts positioned in each of at least two of said holes; and a plurality of electrical conductors terminating in pins, each of said pins being inserted into one of said socket contacts positioned in said holes, said material of said block being heat recovered into engage-

ment with said pins and causing said socket contacts to firmly engage and make electrical contact with their respective pins, said assembly admitting of the subsequent removal of said electrical conductors terminating in pins upon the application of heat.
